(57) **CLAIM**

We claim the ornamental design for a solar powered fishing device, as shown.

DESCRIPTION

FIG. 1 is a top plan view of the solar powered fishing device showing our new ornamental design;

FIG. 2 is top perspective view thereof;

FIG. 3 is a front elevation view thereof;

FIG. 4 is a bottom perspective view thereof; and,

FIG. 5 is a bottom plan view thereof.

Those features depicted with dashed lines do not form a part of the disclosed design.
